UNITED STATES PATENT OFFICE.

PATRICK GALLAGHER, OF NEW YORK, N. Y.

TRICYCLE.

SPECIFICATION forming part of Letters Patent No. 388,963, dated September 4, 1888.

Application filed April 20, 1886. Serial No. 271,255. (No model.)

To all whom it may concern:

Be it known that I, PATRICK GALLAGHER, of the city of New York, county and State of New York, have invented a new and Improved 5 Tricycle, of which the following is a full, clear, and exact description.

This invention relates to tricycles, and has for its object to provide a tricycle so constructed that it may be easily operated and 10 guided.

The invention consists in a tricycle constructed and arranged as hereinafter described and claimed.

Reference is to be had to the accompanying 15 drawings, forming a part of this specification, in which similar figures of reference indicate corresponding parts in all the views.

Figure 1 is a perspective view of a tricycle constructed in accordance with this invention. 20 Figs. 2 and 3 are details thereof, illustrating the support for the guide-wheel; and Fig. 4 is a detail view of the operating-handle and connections.

In the construction of the invention a front 25 guide-wheel, 1, and rear driving-wheels, 2, are mounted on a light and strong iron framework, 3, provided with a suitable seat, 4. The machine is propelled by a crank-handle, 5, mounted in arms 6, pivoted, as at 7, to uprights 30 8 on the frame 4, and secured in position by adjusting-bolts 9, passing through slots 10 in their lower ends and engaging the uprights 8.

Upon one end of the crank-handle 5 is secured a toothed gear-wheel, 11, connecting by 35 an endless chain, 12, with a toothed gear-wheel, 13, adjacent to one of the rear driving-wheels, 2. To enable the machine to turn, the opposite driving-wheel is loosely mounted on its axle, while the driving-wheel adjacent to 40 gear-wheel 13 is fixed to its axle and turns with it and the gear-wheel 13, also fixed thereon. By means of this construction the machine may be easily driven by the handle 5, which is conveniently in reach of a person occupying 45 the seat 4, and the chain 12 may be loosened or tightened through the adjustment of the pivoted arms 6 by means of the adjusting-bolts 9 and the slots 10. The position of the crank-handle 5 may be also adjusted with reference 50 to the seat 4, to provide for arms of different

length, by means of the pivoted arms 6 and bolts 9. In this case the chain 12 is shortened by removing one or more of its links. The guide-wheel 1 has its bearings in a fork, 14, having a post, 15, extending through the 55 bracket-arms 16 of a U-shaped frame secured to the front of the frame 3 and braced by a bent rod, 17. The post 15, which is adapted to turn in the bracket arms 16 by the movement of the foot-piece, is inclosed in a tubular 60 sleeve, 18, located between the bracket-arms 16, and is formed with a square portion, 19, with which the end of an arm, 20, is engaged by means of the square hole 21. The lower 65 end of the arm 20 is provided with the foot-piece 22, having upturned ends or guards 23. The upper end of the post 15 is formed with a screw-threaded end, 24, projecting above the upper bracket-arm 16 and provided with a 70 securing-nut, 25. The latter is formed with a handle, 26, by means of which the nut 25 may be conveniently operated at any time. The turning action of the wheel 1 with its post 15 may be governed by tightening or loosening 75 the nut 25.

It will be seen that upon tightening the nut 80 the bracket-arms 16, the sleeve 18, the upper end of the arm 20, and the fork 14 will be tightened together, thereby restricting the turning movement of the wheel 1 and post 15 and preventing the wheel from violent wabbling in its movement over rough ground.

By means of this invention it will be seen 85 that a simple, serviceable, and effective tricycle is provided.

Having thus described my invention, what I claim as new, and desire to secure by Letters Patent, is—

1. The combination, with the driving-wheel and its axle, the chain-wheel mounted on the latter, and uprights forming part of the machine-frame, of the arms 6, pivoted to said uprights and having slots in their lower ends, the adjusting-bolts passing through said slots, the crank-handle mounted in the upper ends of 90 said arms, and the chain-wheel and endless chain, all as shown and described, whereby the adjustment of the arms regulates the tension of the endless chain, as specified.

2. A tricycle having a guide-wheel, 1, 100

mounted in fork 14, having turning-post 15, formed with the square portion 19 and screw-threaded end 24, in combination with the bracket-arms 16 on the main frame of the machine, the sleeve 18, located between bracket-arms 16, the adjusting-nut 25, with handle 26, and the arm 20, having square hole 21 at one

end engaging the square portion 19 of post 15, and at the other end the foot-piece 22, substantially as shown and described.

PATRICK GALLAGHER.
